CLAIM

The ornamental design for a pet umbrella, as shown and described.

DESCRIPTION

FIG. 1 is a first perspective view of a pet umbrella showing the claimed new design;

FIG. 2 is a second perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plane view thereof;

FIG. 8 is a bottom plane view thereof.

FIG. 9 is a perspective view of the pet umbrella shown with the handle and pole in an alternate state; and,

FIG. 10 is a perspective view of the pet umbrella shown in use for ease of disclosure.

The broken lines depict environment that forms no part of the claimed design.

1 Claim, 10 Drawing Sheets
